[57] CLAIM

The ornamental design for a poultry coop or similar article, as shown and described.

DESCRIPTION

FIG. 1 is an isometric view of a poultry coop or similar article showing our new design;

FIG. 2 is a top plan view thereof;

FIG. 3 is an elevational view taken from one side thereof, the opposite side being a mirror image of the side shown;

FIG. 4 is an elevational view taken from one end thereof, the opposite end being the same as the end shown; and

FIG. 5 is a bottom plan view thereof.

FIG. 2

FIG. 3

FIG. 4
